UNITED STATES PATENT OFFICE.

JACOB H. MEYER, OF NEWARK, NEW JERSEY, ASSIGNOR TO MEYER & GROSS, A CORPORATION OF NEW JERSEY.

DESIGN FOR A FINGER RING.

Application filed February 20, 1926. Serial No. 16,621. Term of patent 7 years.

To all whom it may concern:

Be it known that I, JACOB H. MEYER, a citizen of the United States, and a resident of Newark, in the county of Essex and State of New Jersey, have invented a new, original, and ornamental Design for Finger Rings, of which the following is a specification, reference being had to the accompanying drawing, forming part thereof.

Figure 1 is a side elevation of a finger ring showing my new design, and

Figure 2 is an edge elevation of the ring.

I claim:

The ornamental design for a finger ring, as shown.

JACOB H. MEYER.
